UNITED STATES PATENT OFFICE.

THOMAS ALEXANDER, OF CAMBRIDGE, MASSACHUSETTS.

ARTIFICIAL SLIDING-HILL.

SPECIFICATION forming part of Letters Patent No. 269,554, dated December 26, 1882.

Application filed March 31, 1882. (No model.)

To all whom it may concern:

Be it known that I, THOMAS ALEXANDER, of Cambridge, in the county of Middlesex and State of Massachusetts, have invented a new and useful Improvement in Artificial Sliding-Hills, of which the following is a specification.

My invention relates to an improvement in artificial sliding-hills which may be in condition for use all the year round, but are especially adapted during the heated or milder seasons of the year.

The invention consists in constructing the hill with grooved ways or track, to be used in combination with sleds of peculiar construction and adapted to the grooved ways, so as to insure safety to the occupants of the sled while gliding swiftly down.

The invention further consists in continuing the lower end of the track or tracks with a curve, by which the sleds are conducted to an ascending track on which is arranged an endless chain or belt provided with hooks which engage with loops on the sleds, whereby the latter are drawn to the top of the hill again, either with or without their occupants.

The invention further consists in certain details more fully hereinafter described.

In the accompanying drawings, Figure 1 represents a side elevation of a sliding-hill embodying my invention. Fig. 2 is a plan or top view of the same. Fig. 3 is an enlarged cross-section of the hill. Fig. 4 is a plan view of one of the starting-tables. Fig. 5 is a section on line $y-y$ of Fig. 4. Fig. 6 is a longitudinal section of a sled designed for use with the sliding-hill. Fig. 7 is a front elevation of the sled. Fig. 8 is a view of the device attached to the sled for engaging with the hooks on the endless belt. Fig. 9 represents a device for disengaging the hooks. Fig. 10 represents a buffer placed on the rear of the sled. Fig. 11 is a side view of the brake attached to the sled. Fig. 12 is a plan or top view of the same. Fig. 13 is a modification of the method of arranging the endless belt.

A is a platform, supported upon a suitable frame-work of any desired size or height. From one side of the platform A descends an inclined plane, B, to a point near the ground, when it ascends in the opposite direction, as shown at B', so as to check the velocity of the

sled. The inclined plane B is constructed with one or more grooved ways, C, as shown in Fig. 3, and on each side of the ways C are grooves C'' C'', in which the feathers q q on a sled (see Fig. 7) engage, as hereinafter explained. In the center of each of the ways C is fitted a guide, D, which is grooved longitudinally on its upper surface, as seen in Fig. 3. The grooved ways extend from the top of the inclined plane B to the bottom, where they turn in a circular line to the return course C', which may be made with or without side grooves; but the center guides, D, are continued up. The platform A is also provided with corresponding center guides, D, as shown, thus forming a continuous path for the guidance of the sleds.

E represents rollers which may be placed on the down-tracks to lessen the friction, and thus give additional velocity to the sleds.

At the bottom, on the curved portion of the track, are placed rollers F for the sleds to travel on, thus reducing the friction. These rollers I design to make beveled inwardly, so as to cause the sleds to keep the track in turning the curve. I also place rollers on the return-course for the purpose of reducing the friction, thus requiring less power to draw up the sleds. On the platform A are also placed beveled rollers similar to those at the bottom.

The rollers may be driven by power, if desired, and the ways C, I prefer to make of metal.

The starting-table I, Figs. 4 and 5, is made of metal or wood hinged to the front edge of the platform. Upon this table are fitted side pieces, i, provided with grooves corresponding to the grooves in the downward ways. This table is elevated at the rear by means of a hand-lever, J, fixed on a rod, L, to which is attached a cam or lever, K, under the center of the table, so that by moving the lever J the table is raised so as to bring its surface to the same inclined plane as the downward course. When the sled leaves the table I the latter assumes a level position.

On the shaft, carried in suitable bearings under the platform A, and driven by any desired power, is fixed the pulley N. At the lower end of the hill is also fitted a pulley, O, over which pulleys passes the endless chain, rope, or

belt M, which is provided with suitable hooks for taking into a device on the under side of the sleds, so as to allow them to be drawn up by the belt. I have shown the endless belt 5 slightly out of the center of the track; but it might be placed in the center of the grooved guide, as shown in Fig. 13.

By the side of the curved portions of the tracks, at the bottom of the inclined plane, I 10 provide hand ropes or rails H, the object of these ropes or rails being to enable the occupant of the sled to check the speed at which he is going; or, if the velocity of the sled should not be sufficient to carry him round to 15 the endless belt, he can take hold of the rail and thus draw himself along, so that one of the hooks can catch the sled and carry it up.

The runners Q' of the sleds Q, I make of wood or metal rounded at both ends, and on 20 the sides are fitted feathers q q, to take into the grooves of the ways C, for the purpose of preventing the sleds from leaving or being thrown from the track. At or near the rear of the under part of the sled is fitted a roller or wheel, 25 a, which runs in the groove of the center guide, D but the grooves in the down-tracks are so deep that the roller a does not touch; but when the sled reaches the curve at the lower portion of the course the roller a then bears on the 30 bottom of the groove in the center guide, D.

On the bottom of the sled is also fitted a device, Fig. 8, for the hooks on the endless belt 35 M to take into. This device is composed of two metal jaws, c c, attached to a piece of metal, b, which is firmly secured to the sled. These jaws overlap each other at the lower ends, as shown, and are held in position by means of a spiral or other spring, d. The object of this 40 device is that when in its normal position a hook, coming in contact with it, cannot pass by, but carries the device with it until it comes into contact with another device, R, (shown in Fig. 9,) which is placed at the top of the return-course, the points e e entering the space 45 between the jaws c c, and as the jaws slide over the edges of the plate S they are forced open, so as to allow the hook to pass through. The plate S is supported by two standards, f f, secured to the floor of the platform A. These 50 standards f f are far enough apart to allow the endless belt M to pass freely between them.

At the front of the sled I provide a brake, (see Fig. 11 and 12,) which is composed of two 55 clamping-jaws, g g, at the end of levers h h. These levers cross each other and are pivoted together at j. The outer ends of the levers h h are provided with eyes k k, to which is connected the rod m by the bars or links l l. The rod m has a screw-thread, which works in the 60 nut n, so that as the hand-wheel p is turned in one direction the rod m is raised and the eyes k k brought closer together, and the jaws g g caused to grip the center guide, D, and when the hand-wheel p is turned in the opposite direction the jaws g g are opened and pass free of the guide.

At the back of each of the sleds I place a

buffer, (shown enlarged in Fig. 10,) the head i being of leather, fitted to a bell-mouth piece, s, connected to the plate t, which is made to 70 fit and is screwed onto the sled.

Stairs P are provided for access to or from the platform A, and stairs P' for access to or from the lower part of the inclined plane.

When in use a sled is placed on one of the 75 starting-tables I. The corresponding lever, J, is then operated, which raises the table I to the same angle as the inclined plane. The sled then slides down the grooved ways until it comes to the bottom of the hill, when it turns 80 the curve on the upward incline, which tends to break the velocity. When it reaches the top of the incline it again descends until it comes into position for a hook on the endless belt M to take into the device on the bottom 85 of the sled, which is thus carried up to the top of the hill and onto the platform A, when it is disengaged by the device shown at Fig. 9, and the hook is free to pass. The attendant then pushes the sled along the curved guides on 90 the platform to the starting-table, when the journey is again resumed without the occupants being obliged to leave the sled.

Although I have shown three down courses and one return-course, I would have it understood that any number may be used, and, instead of having the return-course on one side, there might be one on each side or at the center.

The sliders can walk up the stairs P to the 100 platform A, or they can ascend by the stairs P' and be drawn up in a sled. A level space of any desirable length may be interposed between the lower end of the main hill and the upward incline before passing upon the curve. 105 Different portions of the hill may be more or less inclined than other portions, if desirable. A roof or covering may be placed over the platform A, if desired.

What I claim as my invention is—

1. The combination, with the inclined plane B, of the grooved ways C and the side grooves, C' C'', as and for the purpose specified.
2. The combination, with the grooved ways C, of the center guide, D, as set forth.
3. The combination, with the grooved ways C and side grooves, C' C'', of a sled or carriage, Q, having runners Q' Q', provided with feathers q q, which engage with the said side grooves, substantially as shown and described.
4. The brake composed of the clamping-jaws g g, the levers h h, the connecting-links l l, rod m, and hand-wheel p, as and for the purpose set forth.
5. In a sliding hill, the combination, with the inclined plane B, provided with grooved ways C, of a return-way provided with an endless chain or belt having hooks which engage with loops on the sleds, whereby the sleds, with or without their occupants, are drawn up 125 to the platform A, substantially as specified.
6. The hinged table I, arranged at the top of the incline B, and operated by means of a lever to adjust the said table to the level of

the platform A or tilt it to an incline corresponding with the incline plane B, substantially as set forth.

7. In a sliding hill, the combination, with an endless chain or band, M, provided with hooks, of a loop, C, attached to a sled or carriage, as and for the purpose specified.

8. The combination, with the curved grooved ways of the track, of the beveled friction-rollers, as and for the purpose set forth.

9. The hook-detacher R, in combination with the jaws c e, as and for the purpose set forth.

10. The wheel or roller a on the under part

of the sled, in combination with the grooved 15 guide D, as and for the purpose specified.

11. The sled provided with an attaching-loop, a brake, a buffer, and projections or feathers at the outer sides of the runners, as and for the purpose specified. 20

In testimony whereof I have signed my name to this specification in the presence of two subscribing witnesses.

THOS. ALEXANDER.
